(57) **CLAIM**

The ornamental design for a combined portable wireless power charger and charging stand, as shown and described.

DESCRIPTION

FIG. 1 is a front view of a combined portable wireless power charger and charging stand showing our new design;

FIG. 2 is a rear view thereof;

FIG. 3 is a left side view thereof;

FIG. 4 is a right side view thereof;

FIG. 5 is a top view of thereof;

FIG. 6 is a bottom view thereof;

FIG. 7 is a top front right side perspective view thereof;

FIG. 8 is a bottom front left side perspective view thereof;

FIG. 9 is a top rear right side perspective view thereof; and,

FIG. 10 is a bottom rear left side perspective view thereof.
